UNITED STATES PATENT OFFICE

CARL A. RUFF, OF LOS ANGELES, CALIFORNIA, ASSIGNOR TO COMMERCIAL IRON WORKS OF LOS ANGELES, OF LOS ANGELES, CALIFORNIA, A CORPORATION OF CALIFORNIA

STEREOTYPE-PLATE-CASTING MACHINE

Application filed August 21, 1928. Serial No. 300,990.

My invention is a stereotype plate casting machine.

An object of my invention is the construction of a stereotype plate casting machine in which the mold may be locked in a horizontal position and the cope opened by pivoting to one side for insertion of the matrix; and in this operation the drag is locked in a stationary position. For operating the mold is pivoted on a horizontal axis extending transversely of the mold so that the mold may be inclined with one end up and the other adjacent the floor. This positions the pouring gate at a convenient height above the floor for the pouring of the metal.

Another object of my invention is the construction of a mold for a stereotype plate casting pivoted on a horizontal axis transversely of the mold, the axis being towards one end and such end has a counterweight to balance the mold and the metal poured therein. This pivotal construction adjacent one end of the mold is adapted to position the pouring gate when the mold is inclined at a convenient elevation above the floor for easy pouring.

Another object of my invention is in the manner of pivoting the cope to one side of the drag of the mold and utilizing a pair of legs connected to the opposite side of the cope from the pivotal mounting of the drag. These legs have a lever construction to loosen the cope from the drag after casting and may be grasped as handles to swing the cope into the open position, the cope in this position being supported on the legs.

Another object of my invention is in the manner of holding and pressing the cope into a proper fit with the drag, this being done by a pair of rock shafts on opposite sides of the drag, and having clamps frictionally mounted thereon.

The clamps are adapted to engage over the rim of the cope and by means of an eccentric action between the clamps and the rock shafts on the completion of the turning movement of such shafts, the clamps after being rocked into engagement with the cope are given a pull downwardly thus forcibly locking the cope and the drag.

Various other features of novelty will be apparent from the following description and the claims; and my invention is illustrated in the accompanying drawings, in which:

Fig. 1 is a perspective view of my machine in the horizontal position with one side of the cope released and prior to opening the cope,

Fig. 2 is a perspective view with the mold in position for pouring,

Fig. 3 is a front end elevation partly broken away,

Fig. 4 is a central longitudinal section on the line 4—4 of Fig. 3, in the direction of the arrows,

Fig. 5 is a detail elevation on the line 5—5 of Fig. 3 in the direction of the arrows,

Fig. 6 is a side elevation showing one of the rock shafts and clamps frictionally connected thereto,

Fig. 7 is a transverse section on the line 7—7 of Fig. 6 in the direction of the arrows showing the clamps in locking position,

Fig. 8 is an elevation similar to Fig. 6 showing one of the clamps in the open or unlocked position,

Fig. 9 is a section on the line 9—9 of Fig. 8 in the direction of the arrows,

Fig. 10 is a transverse section through the mold showing in elevation the device actuated by the legs to open the cope,

Fig. 11 is a longitudinal section on the line 11—11 of Fig. 10 in the direction of the arrows,

Fig. 12 is a partial detail section similar to Fig. 9, illustrating the eccentric action of the rock shaft.

In constructing the casting machine I employ a suitable frame designated generally by the numeral 11, this having a pair of standards 12 on opposite sides, on which standards there is mounted a pair of short pivot shafts 13 forming the pivotal connection of the mold designated generally by the numeral 14 to the frame. This connection is by providing the drag 15 with lugs 16 on the side through which the pivot shafts 13 extend. (Note Figs. 1, 3 and 5.) The drag is trough shaped and has a rim 17 at one end and

55

85

200

at the other end is provided with an inclined plate 18 adapted to form a rest in pouring the metal in the gate 19. At each edge of the drag there is a removable rim bar 20 confining the metal pouring between the side margins of the cope and the drag; and at the lower end a removable segment of a ring 20' to confine the metal between the cope and drag.

10 The drag at one end is provided with pivot pins 21 from which depend curved links 22, these links having a heavy counterweight 23 connected thereto, the counterweight fitting between the forward legs 24 of the frame, 15 there being a guard plate 25 in front of the counterweight. The frame is provided with lugs 26 through which extend set screws 27, these set screws being adjustable to engage the bottom of the counterweight when in its 20 lowermost position and carry their weight. This counterweight swings from the position shown in Figs. 1 and 4 to that shown in Fig. 2 in the operation of the machine. A matrix 27' is fitted in the drag.

25 The cope designated generally by the numeral 28 is formed with a transverse curvature concentric with that of the drag and at the upper end has a sloping section 29 which functions with the upper end of the drag to 30 form the gate 19. At the lower end of the cope there is a transverse section 30 which fits against the end rim 17 preventing the escape of the metal in pouring. Hinge leaves 31 are attached to one side of the cope, 35 there being two such leaves illustrated, and these are pivoted to the fixed arm 32 of the hinge connected to the drag by hinge pintles 33. A pair of legs 34 are fitted in a block 35 shown in detail in Figs. 10 and 11, and these 40 blocks are mounted on pivot pins 36 mounted in ears 37 secured to the upper part of the cope on the opposite side to that of the hinge leaves 31.

45 Formed integral with the blocks 35 there are short bow-shaped pressure levers 38 which have a pressure exerting end 39 adapted to bear against the upper outside edge 40 of the drag. There is a set screw 41 which extends through the pressure lever 38 and is adapted to have its lower end with a slight clearance above the edge 42 of the cope. This set screw may be adjusted by a clamping nut mounted thereon. There is also a set screw 43 which extends through 55 the pressure lever and bears on the pin 36 forcing this pin to rock with the block 35 in the journals in the ears 37.

50 On each of the blocks 35 there is an abutment boss 44 which is adapted to have a slight clearance from the upper curved surface 45 of the cope when the pressure end 39 is in contact with the edge 40 of the drag.

55 The action of the legs and the pressure lever 38 is first to relieve the cope after

pouring of the metal. The operator may stand at one side of the cope and by a quick thrust or a pull on the upper ends of the legs 34 he may rock the pressure levers so that the pressure end 39 forcibly engages the edge 40 of the drag, thus slightly elevating the cope until it comes in contact with the adjustable set screw 41. This action loosens the cope from the cast metal and allows it to be tilted upwardly on the hinge 75 pins 33 until the ends of the legs rest on the floor thus exposing the complete interior of the drag.

70 The clamping and locking mechanism for the cope and drag comprises a pair of rock shafts 46 mounted on opposite sides of the drag. These are illustrated as being journaled in a pair of closed journals 47 adjacent the ends of the drag and open journals 48 in the intermediate positions. As shown 75 in detail in Figs. 6 through 9, and 12, the shaft has a reduced diameter 49 at the journals and an enlarged diameter 50 between the journals, and on this enlarged diameter hook-shaped clamps 51 are frictionally mounted.

80 This friction mounting utilizes an annular groove 52 in the enlarged portion 50 in which groove fits the tongue 53 of a slidable pin 54, this pin being mounted in a cylindrical extension 55 of the clamps 51, there being a pressure spring 56 bearing against the pin 54 and the adjustable screw plug 57. This pressure is sufficient so that normally 85 when the rock shaft is partially rotated by the hand crank 58 the clamps are carried with the shaft.

85 Each of the clamps is provided with an adjustable set screw 59 adjacent its outer end and on the inner face there is a fixed 95 boss 60. This fixed boss is adapted to engage the outer surface 61 of the drag adjacent its edge and the set screw to contact with a beveled surface 62 on the upper edge of the cope. (Note Fig. 7.) There is also a boss 63 on the end of the extension 55, this boss being adapted to come in contact with the lower surface of the drag below the rock shaft as indicated at 64. (Note Fig. 9.)

95 The action of the clamps is as follows, presuming the mold to be in a horizontal position and the cope to be closed over the drag as shown in Fig. 1: On the rocking movement of one of the rock shafts 46 through the medium of the crank 58 the 100 clamps are shifted from the position shown in Fig. 1 to that shown in Figs. 2 and 3 until the set screws in each of the clamps contact with its abutment surface 62 and the bosses 60 engage the outside of the drag 105 adjacent its edge. As the reduced portion of the shafts 46 journaled in the journals 47 and 48 is eccentric to the surface 50 on which the clamps have frictional rotation 110 the further movement of the hand lever 58 115

rocking the shaft 46 gives a downward pull on the clamps 51 thereby pressing the cope into a tight fit with the marginal edges of the drag. On the releasing movement the 5 first action of the rock shafts is to loosen the clamps by giving them a slightly upward movement relative to the journals 47 and 48 until they are released from the cope and then the further movement carries the 10 clamps through the medium of the frictional engagement with the rock shaft from the position of Fig. 7 to that of Figs. 9 and 1, the bosses 63 contacting with the under portion of the drag.

15 The latch device designated generally by the numeral 65 has a handle 66 mounted on a pivot stud 67 secured to a boss 68 which is preferably formed integral with the standard portion 12 of the frame 11 and on one 20 side. The stud 67 has a latch finger 69 which is adapted to engage on either side of a nub 70 on a boss 71 formed on one of the lugs 16 extending outwardly from the drag. (Note Figs. 1 and 5.) In Fig. 5 the 25 position is illustrated in which the mold is in a horizontal position and tilting of the mold downwardly to the position of Fig. 2 is prevented by the latch finger 69 bearing against the nub 70 and the boss 71, and any 30 rotating movement thrusting the end of the finger against the nub 70 and the boss 71. The handle 66 is first thrust upwardly and then the cope and drag are tilted up by the operator engaging the two handles 72 which 35 extend towards the front part of the machine from the top of the cope. When the mold is tilted into the position of Fig. 2 the latch finger 69 engages on the opposite side of the nub 70. The adjustable screw 73 40 mounted in a cross rod 74 between the bottom rails 75 of the frame limit the tilting motion of the mold. The two sides of the frame are held in adjusted position by bolts 76 having sleeves 77 thereon. It will be 45 noted that when the mold is tilted in the position of Fig. 2 that the pouring gate is at a convenient elevation above the floor so that an operator may stand in front of the machine and pour the molten metal through 50 the gate.

A feature of my invention is that the mold is pivotally mounted on the frame near the upper end when the mold is tilted and therefore the pouring gate is at a convenient 55 height above the floor level so that the metal may be readily poured into the gate by a person standing on the floor.

The function of the counter-weight is to 60 aid the tilting of the mold back to the horizontal when the metal has been poured therein, that is, when the casting has been made, as it will be seen by the relation of the pivot points of the mold to the frame that a large proportion of the stereotype plate is 65 on the side of the pivots opposite the coun-

ter-weight. Therefore with this counter-weight it is comparatively easy for a person to tilt the device from the inclined position into the horizontal. Moreover, the counter weight helps to balance the part of the mold on one side of the mounting pivots.

70 Various changes may be made in the principles of my invention without departing from the spirit thereof, as set forth in the description, drawings and claims.

75 I claim:

1. A stereotype plate casting machine having a supporting frame, a mold mounted thereon, a pivotal mounting for the mold on the frame transverse to the longitudinal axis of the mold, such pivotal mounting being adjacent the upper end of the mold, a counterweight connected to the upper end of the mold, means to swing the mold from a horizontal to an inclined position, and a pouring gate at the top of the mold when in the inclined position, the counterweight aiding the return of the mold from the inclined to a horizontal position after casting of the plate.

80 2. A stereotype plate casting machine comprising in combination a frame, a mold having a drag, a pivotal mounting for the drag on the frame transverse to the longitudinal axis of the mold, a cope hingedly connected to one side of the drag, the axis of the hinge being parallel to the axis of the mold, means securing the cope and the drag, and a releasing means having a lever and 85 jarring action between the cope and drag to loosen the cope and the drag after pouring the metal, the releasing means including a leg connected to the cope and a lever means engaging the drag, the said leg being adapted to partly support the cope in an open 90 position.

95 3. A stereotype plate casting machine comprising in combination a supporting frame, a mold having a drag, the drag being pivotally connected to the frame on an axis transverse to the drag to allow tilting from a horizontal to an inclined position, a cope hingedly connected to one side of the drag, clamping means securing the cope and the drag on both longitudinal sides thereof, a 100 leg pivotally connected to the cope, and having a pressing lever to engage the drag, the leg being adapted to partly support the cope when in an open horizontal position.

110 4. A stereotype plate casting machine as 120 claimed in claim 7, the pivotal connection of the drag and the frame being adjacent one end of the drag, a counterweight adjacent such end, the said end forming an upper end when the mold is inclined, and a gate 125 formed by part of the drag and the cope at the end having the counterweight, the counterweight aiding the return of the mold from the inclined to a horizontal position after casting of the plate.

5. In a stereotype plate casting machine having a drag and a cope hinged together along one side, a longitudinal rock shaft journaled on at least one side of the drag and having clamps to engage the cope on a rocking movement of the shaft, and an eccentric connection between the shaft and the clamps on further movement of the shaft to draw the clamps into close engagement with the cope and on a reverse movement of the shaft the eccentric first releasing the clamps and then shifting the clamps clear of the cope to allow opening of the cope and the drag. 10
6. In a stereotype plate casting machine having a mold with a drag and a cope hinged together along one side, means to shift the mold from a horizontal position for installing a matrix and removing a casting to an inclined position for pouring the metal for the casting, a pair of rock shafts journaled on opposite sides of the drag having clamps, said clamps being frictionally connected to the shaft and on a first movement thereof being shifted transversely from a position clear of the cope to a position contacting with the cope, and an eccentric connection between the shaft and the clamps on the further movement of the shaft 20 to move the clamps into a pressing relation to the cope and on a reverse movement to first relieve the pressure and then to move the clamps transversely clear of the cope. 25
7. In a stereotype plate casting machine as claimed in claim 12, the mounting of the mold comprising a horizontal pivotal connection between the drag and the supporting frame transverse to the mold to allow tilting from a horizontal to an inclined position, and a gate formed by the drag and the cope at the uppermost end when the mold is inclined and a counter-weight pivotally connected to the upper end of the drag. 40
8. In a stereotype plate casting machine as claimed in claim 12, a leg pivotally connected to the top of the cope, a pressing lever connected to the leg having a pressure exerting end adapted to bear on the upper outside edge of the drag, a set screw in the lever to restrict the movement of the cope, the said legs and the pressure lever being adapted to loosen the cope and the drag after casting, and the legs forming a partial support for the cope when in a horizontal open position. 50
9. A stereotype plate casting machine having a frame with a mold having a drag, a pair of lugs extending laterally from the drag and pivotally connected to the frame, a boss extending from one of the lugs having a nub thereon, a latch pivotally connected to the frame and having a finger adapted to engage on opposite sides of the nub, the mold 60 swinging on the pivotal connection of the lugs and the frame from a horizontal to an inclined position. 65
10. A stereotype plate casting machine having a mold with a drag and a cope, the drag being pivotally connected to a supporting frame on an axis transverse to the mold, a tilting handle connected to the cope at its upper end, means to clamp the cope and the drag, a counterweight connected to the upper end of the drag, means to support the counterweight when the mold is in a horizontal position, and means to stop the movement of the mold when in an inclined position. 70
11. In a stereotype plate casting machine a mold having a drag and a cope, the cope being hingedly connected to one side of the drag, a leg pivoting on a longitudinal pin mounted on the cope, a pressure lever connected to the leg and having a pressure end 80 to engage the upper edge of the drag, a boss connected to the leg to engage the upper surface of the cope, the rocking movement of the leg causing a releasing action of the cope and the drag after casting, and the leg forming a partial support for the cope when in a horizontal open position. 85
12. In a stereotype plate casting machine, the combination of a drag and a cope hinged together along a longitudinal edge, a longitudinal rock shaft on each side of the drag, clamps mounted on each rock shaft, said clamps engaging the cope on rocking of the said shafts, and clamping the cope to the drag. 90
13. In a stereotype plate casting machine having a cope and a drag pivotally connected along one side, a rock shaft on each side of the drag having cam surfaces, clamps having a part encircling the cam and frictionally connected thereto, the free ends of said clamps being adapted to engage the cope, the rocking movement of the shafts bringing the clamps into contact with the cope and the further movement tightening the said clamps. 100
14. In a stereotype plate casting machine having a drag and a cope hinged together along one side, clamps to secure the cope and the drag in casting position, a releasing device having a first lever pivotally connected thereto, a bow-shaped pressure lever connected to the first lever, said pressure lever having an end to engage the marginal edge of the drag, whereby a transverse push from the hinge side on the first lever rocks the pressure lever to bear against the edge of the cope and thereby loosen the drag from the cast plate along one side and a pull operates the cope from the drag, the said first lever being adapted to rest on a support and retain the cope in its open position. 110
15. In a stereotype plate casting machine having a drag and a cope hinged together along one side, a rock shaft extending along 120

one side, clamps mounted on said shaft to interengage the drag and the cope by a swinging transverse movement on the rocking of the shaft, and means actuated by the shaft to exert pressure on said clamps when interengaged to draw the cope and the drag into close relation.

16. A stereotype plate casting machine comprising in combination a frame, a mold having a drag, a pivotal mounting for the drag on the frame transverse to the longitudinal axis of the mold, a cope hingedly connected to one side of the drag, the axis of the hinge being parallel to the axis of the mold, means securing the cope and the drag, a releasing means having a hand operated lever on the cope and a pressure lever connected to the hand operated lever to loosely engage the drag and when the cope and drag are in casting relation, whereby a rocking motion of the hand lever may give a hammer-like jarring action by the pressure lever on the drag to loosen the cope from the cast plate.

25 17. In a stereotype plate casting machine, a drag and a cope hinged together along one side, the hinge being parallel to the axis of the mold, a securing means to hold the cope and the drag in casting position, a releasing means comprising a hand lever pivotally mounted on the cope and having a pressure lever rigidly connected thereto, the pressure lever being adapted to extend beyond the marginal edge of the cope and engage the margin of the drag opposite the hinge, the pressure lever having a slight loose motion on movement of the hand lever, whereby on a thrust of the hand lever a hammer-like jarring action may be given on the drag, thereby loosening the cope from the cast plate.

18. In a stereotype plate casting machine as claimed in claim 25, the pressure lever having an abutment boss adapted to engage the upper side of the cope in the rocking movement and to transmit pressure from the hand lever to the cope in opening the cope from the cast plate.

19. In a stereotype plate casting machine as claimed in claim 24, the hand lever being adapted to form a leg and support the cope when in its open position.

20. In a stereotype plate casting machine having a cope and a drag hinged together at one side, means to secure the cope and the drag in a casting position, a loosening device pivotally connected to the cope and having a lever to be grasped by the hand and a second lever to bear on the edge of the drag and a pressure means to engage the cope and restrict the movement of the lever, whereby a levering push from the hinge side of the handle actuates the second lever to engage the drag and loosen the cope and the drag along one marginal edge and a

pull on the handle brings the abutments means into engagement with the cope and restricts the movement of the handle, whereby a further pull on the handle operates to raise the cope from the drag on its hinged connection.

21. In a stereotype plate casting machine having a drag and a cope hinged together along one side, a plurality of clamping means therefor and positioned along at least one side, a thumb movable actuating device for all of the said clamping means, having a partial slipping action between said device and the said means, whereby the operation of the said device to actuate the clamping means first interengages the cope and the drag and after a slipping action of any of the clamping means which are not properly engaged, operates to draw the cope and the drag into close engagement.

In testimony whereof I have signed my name to this specification.
